Primary Examiner — Robin V Webster(74) *Attorney, Agent, or Firm* — Morrison & Foerster LLP(57) **CLAIM**

We claim the ornamental design for a faucet head, as shown and described.

DESCRIPTION

FIG. 1 is a front perspective view of a faucet head showing our new design;

FIG. 2 is a side view thereof;

FIG. 3 is a side view of the opposite side of FIG. 2;

FIG. 4 is a rear view thereof;

FIG. 5 is a front view thereof;

FIG. 6 is a top view thereof; and,

FIG. 7 is a bottom view.

The broken lines shown in the drawings illustrate portions of a faucet head that form no part of the claimed design.

1 Claim, 7 Drawing Sheets(56)
